RING AND FINGER GAUGE

Monroe Engelsman, New York, N. Y.

Application November 16, 1933, Serial No. 698,275

2 Claims. (Cl. 33—147)

This invention relates to gauges, and has particular reference to devices such as ring and finger gauges.

One object of the invention is to provide a device of the character described which shall have improved indicating means, and improved means for actuating the same.

Another object of the invention is to furnish a device of the type mentioned having relatively few and simple parts, which can be rapidly assembled and inexpensively manufactured, and which shall be free of backlash and highly accurate for taking measurements, and which shall be durable, reliable, and efficient in use, convenient in operation, and adapted for measuring different kinds of articles or objects, such as a finger, a ring, or a precious stone, and mounted and unmounted jewelry settings.

Other objects and advantages of the invention will become apparent as the specification proceeds.

With the aforesaid objects in view, the invention consists in the novel combinations and arrangements of parts hereinabove described in their preferred embodiments, pointed out in the subjoined claims, and illustrated in the annexed drawing, wherein like parts are designated by the same reference characters throughout the several views.

30. In the drawing:

Figure 1 is a plan view showing a device embodying the invention.

Fig. 2 is an edge view thereof.

Fig. 3 is a plan view of the device with the top plate removed, and parts broken away to show elements of construction.

Fig. 4 is an enlarged sectional view taken on the broken line 4—4 of Fig. 3.

Fig. 5 is an enlarged sectional view taken on line 5—5 of Fig. 1.

Fig. 6 is an enlarged fragmentary plan view with parts removed and showing the gauge locked after being set according to different articles to be measured, shown in dot-dash lines.

45. Fig. 7 is a sectional view taken on line 7—7 of Fig. 3.

The advantages of the invention as here outlined are best realized when all of its features and instrumentalities are combined in one and 50 the same structure, but, useful devices may be produced embodying less than the whole.

It will be obvious to those skilled in the art to which the invention appertains, that the same may be incorporated in several different constructions. The accompanying drawing, therefore, is submitted merely as showing the preferred exemplification of the invention.

Referring in detail to the drawing, 10 denotes a device such as a ring and finger gauge embodying the invention. The same may include a

main or bottom plate 11 of plane form, the outline of which is clearly shown in Fig. 3, and which conforms in general to the outline of the top plate 12, shown in Fig. 1. The bottom plate may have a curved end 13, and may be provided with an integral jaw 14 at said end extending laterally in the plane of said plate. The jaw 14 may be the full thickness of the plate 11 and may have an inner concaved face 15 for seating a finger F as hereinafter described. The end 65 portion of the jaw 14 may have a square gauge surface 16, extending from the concave surface 15, for seating a stone S, and an outer beveled or curved face or edge 17, with a shoulder or rest 18 at an end thereof, so that a ring R may be seated on the surface 17 in resting relation to the shoulder 18.

From the end or head portion 13, the plate 11 extends toward the right with parallel side edges 70 19 and 20, and may have an opposite curved end 21.

The head portion of the plate 11 may have a housing recess 22 therein having a curved wall 23, which at one end merges along a plane surface 24 into the curved seating face 15 of the 75 jaw 14. At its opposite end, the curved surface 22 terminates at a plane surface 25 formed by a cut out or recess 26 which also affords an opposite plane surface 27. The recess 22, which thus communicates with the cut out 26, extends 80 continuously up to the plane wall 28, and an elongated guide recess 29 having opposite parallel plane walls 30, 31. Of these, the wall 30 intersects the cut out wall 27, and the wall 31 intersects the wall 28. Hence it will be noted 85 that the housing recess portions 32, which as above stated is in continuous communication with the recess 22, extends from the edge 23 of the wall 11 up to the wall 30 and also communicates with the recess 29. It will be observed 90 that the wall 30 is considerably longer than the wall 31, since the former extends to the cut out 26, and the latter to the recess 32.

It will be understood that the opposite faces 95 of the wall 11 are plane, and likewise that the bottom faces of the recesses 22, 26, 29 and 32 all lie in a plane, and that these planes are parallel to each other.

Cooperating with the fixed jaw 14, is a movable jaw 33 having gauge surfaces 15, 17, 18 corresponding to those of the fixed jaw. Said jaw 33 may be formed as an integral portion of the slide block 34 from which the jaw extends laterally. The jaw 33 includes a finger piece 35 and the block 34 is undercut along lines 36, 37 110 on opposite faces thereof, so that while the jaw and finger piece are of the same thickness as the device 10, including the cover plate 12, the slide block 34 is of a thickness equal to that of the depth of the recess 32, with the upper face 115

- of the slide block lying in the plane of the upper surface of the wall 11, the arrangement being best seen in Figs. 4 and 7. The slide block may extend into contact with the surface 30, and the adjacent portion 38 thereof may be undercut at 39, so that a relatively thick bar or guide element 40 may be secured thereto by pins or rivets 41 with the guide element extending to the right. The elongated guide element is received in the recess 29, and is longitudinally movable therewith along with the side edges thereof in accurate sliding contact with the surfaces 30, 31. In this manner the movement of the block 34 and of the jaw 33 is accurately maintained.
- 15 Projecting to the left from the slide block 34 and extending into the housing recess 22 along the bottom wall thereof is an arm 42 in the nature of a relatively thin plate. The slide block may be curved and undercut at 43 adjacent to said arm, to provide a substantially circular space in cooperation with the wall 23, when the slide block is in its extreme position at the left. Within this circular space a dial plate 44 is received having a shaft or pin 45 extending therethrough so that the ends thereof may be journaled in alined bearings 46, 47, of the cover plate 12 and of the wall 11 at the bottom of the recess 22, respectively. The dial 44 overlies the arm or plate 42, and is wholly received in the housing recess 22.
- 20 For actuating the dial 44 for rotation, the same may have a coaxial pinion 48 secured to the underside thereof, and which also acts as a spacer between the dial and the bottom wall of the recess 22, and maintains the dial with a suitable clearance above the arm 42. On the upper face of the dial, a spacer disc 49 may be coaxially secured thereto to act between the dial and the cover plate 12.
- 25 30 For rotating the pinion 48, the arm 42 may have a rack 50 which may lie in the plane of the arm 42. This rack may be separated from the arm 42 by an open ended slot 51, whose closed end is enlarged to afford a suitable resilient connection 52 between the end of the arm and the corresponding end of the rack. By this arrangement backlash is avoided, and it will be further noted that the pinion 48 is at the free end of the rack when the guide element 40 is moved toward the left. In this position, in which the engagement between said element and the guide recess 29 is shortened, the maximum resilience of the rack mounting is available for preventing backlash.
- 35 In order to afford additional support for the slide block 34, so that the latter does not depend wholly on the element 40, the arm 42 may have a guide slot 53 receiving a pin 54 fixed to the wall 11 of the device. The pin and slot may also function as a stop means to limit the movement of the slide block, although such motion may also be limited at the surfaces 16 and 28.
- 40 45 To lock the gauge in a set position, a resilient shaped element 55 may be pivotally mounted in the cut out 26 on a pin 56 secured to the wall 11, and located adjacent to the dial 44 so that a finger of the element is adapted to contact an edge of the dial. At the opposite side of the element, a finger piece 57 is pivotally mounted on a pin 58 secured to the wall 11, said finger piece being located in the cut out and projecting therefrom and being swingable from the unoperated position shown in Fig. 3 to the locking position of Fig. 6, in which an end of the finger piece presses against the other finger of the ele-

ment to deform the latter and produce a resilient stop engagement with the dial.

The cover plate 12 may wholly overlie and conform to the shape of the wall 11, and may also have a jaw portion 59 overlying the jaw 14, so that the thickness of the final stationary jaw 60 is the same as that of the one piece movable jaw 33. The lower edge of the cover plate may afford a seat for the edge 36 of the movable jaw. The cover plate may have a millimeter scale 61 adapted to read with a mark 62 on the movable jaw. For the dial 44, the cover plate may have a window 63 having a reference mark 64 to read with a U. S. standard gauge scale 65 on the scale. The cover plate may also have U. S. standard and millimeter scales 66, 67 respectively, arranged for ready conversion therebetween and extending along opposite edges of the plate.

The cover plate may be removably secured to the wall 11, as by screws at points such as 68.

It will be noted that an essential advantage of the invention is that the gauge reading is considerably multiplied by the dial and its actuating means, permitting more accurate measurement. The finger surfaces 15 of the device 100 may be arranged to indicate one size smaller than those at 17 to assure that the ring R will have the required clearance on the finger.

It will be appreciated that various changes and modifications may be made in the device as shown 105 in the drawing, and that the same is submitted in an illustrative and not in a limiting sense, the scope of the invention being defined in the following claims.

I claim:

1. A gauge having an elongated plate having a straight guide recess extending into proximity to one end thereof, a housing recess at the second end of the plate in communication with the guide recess, said plate having a fixed jaw at said second end thereof, a complementary jaw, means movably supporting the latter including a bar movable along the guide recess, a dial rotatably mounted in the housing recess, a pinion coaxially secured to the dial, an arm fixed with respect to said movable jaw and movable therewith, a rack engaging the pinion and connected to said arm, the latter and the rack being movable into the housing recess, and the rack and arm being interconnected at one end and being otherwise spaced from each other whereby the rack resiliently engages the pinion, the connection between the arm and rack being at the ends thereof adjacent to the second end of the plate.

2. A gauge including a main plate and a cover 130 plate, the main plate having a housing recess and an elongated guide recess extending therefrom, a guide bar in the guide recess, a fixed jaw on the main plate, a movable jaw complementary to the fixed jaw, means interconnecting 135 said guide bar and the movable jaw for mounting the latter, said means being located in the housing recess, a rotary dial in the housing recess, actuator means for the dial located in the housing recess and connected to said means for 140 operation thereby, the actuator means including a pinion and a rack meshing with each other, said means having a projecting arm for mounting the rack, said arm, said rack and said pinion underlying the dial, said arm having a guide 145 slot, and a pin on the main plate engaged in the slot, said cover plate closing said recesses and having a window opening for the dial.
